G. C. Wright INVENTOR

UNITED STATES PATENT OFFICE.

GEORGE CURTIS WRIGHT, OF NEW YORK, N. Y., ASSIGNOR TO THE WORCESTER CARPET COMPANY, OF WORCESTER, MASSACHUSETTS.

DESIGN FOR A CARPET.

SPECIFICATION forming part of Design No. 15,183, dated July 29, 1884.

Application filed May 12, 1884. Term of patent 3½ years.

To all whom it may concern:

Be it known that I, GEORGE CURTIS WRIGHT, a resident of the city, county, and State of New York, have invented a new Design for Carpets, of which the following is a specification.

The nature of my design is fully represented in the accompanying photographic illustration, to which reference is made.

I claim—

The design shown for carpets.
